CLAIM

The ornamental design for an operation element for vehicle joystick control as shown and described.

DESCRIPTION

1.1 : front and/or back view

1.2 : Top

1.3 : left and/or right view

1.4 : Perspective

1.5 : view of the operating element in use

In the drawings, the broken lines depict environmental subject matter only and form no part of the claimed design. The design shows an operation element for vehicle joystick control, namely a thumbstick mainly for the use as an operating element incorporated in a joystick. The design has a symmetrical shape such that the front view is identical to the back view and the left view is identical to the right view. Reproduction 1.5 shows the design exemplary in use incorporated in a joystick. No protection is claimed for the areas outlined with dashed lines.
